OTTO BEST, OF SAN FRANCISCO, CALIFORNIA.

FEED DEVICE FOR WATER-SOFTENERS.

1,276,315.

Specification of Letters Patent. Patented Aug. 20, 1918.

Application filed November 5, 1917. Serial No. 200,418.

To all whom it may concern:

Be it known that I, OTTO BEST, a citizen of the United States, residing at San Francisco, in the county of San Francisco and State of California, have invented new and useful Improvements in Feed Devices for Water-Softeners, of which the following is a specification.

This invention relates to apparatus for softening water by the addition of chemical reagents, and the object of the present invention is to provide a device for feeding a chemical reagent either in solution, as soda ash, or in suspension, as lime, or both, to a continuously flowing stream of hard water in the exact proportion necessary, which will be very sensitive to variations in magnitude of the stream of hard water within a wide range of variations.

In the accompanying drawing the figure is a vertical section, parts being shown in side elevation, of a softening apparatus in which my improved feed device is employed.

Referring to the drawing, 1 indicates a pipe for supplying hard water, and 2 indicates a tank for containing the chemical reagent for softening the water. The pipe 1 discharges into a water-distributing vessel 3, from which the water flows through a bypass pipe 4 into a central section 5 of a softening or reacting chamber 6. The pipe 4 is controlled by a valve 7 by which the rate of the flow of the water can be varied as desired. The hard water also flows from the vessel 3 through a pipe 8 discharging into a vessel 9, suspended, as shown at 10, from an arm 11 of a balance lever 12, pivoted at 13 on a bracket 14 depending from the bottom of the vessel 3. From another arm 15 of said lever 12 depends a weight 16 adjustable on the arm 15 so that it exactly balances the vessel 9, when the latter is empty, and other parts attached to the arm 11, as will hereafter be described. The vessel 9 has a hole 17 in its bottom through which the water escapes and falls into the central section 5 of the softening chamber 6. But when water is in the vessel 9, said vessel is depressed by the weight of the water therein. The lower end of the pipe 8 is so arranged that the water discharges therefrom in a lateral direction in order to prevent the impact of the water from causing the depression of the vessel 9 and to use only the weight of the water to

cause the depression of said vessel. A depending arm 20, rigidly attached to the balance lever near its fulcrum, hangs vertically when the vessel is empty, and carries a weight 21 which always tends to restore the balance lever to its normal position in which the arms 11 and 15 extend horizontally.

From the outer end of the arm 11 is pivotally suspended a cap 22 into which is screwed the upper end of a pipe or conduit 23, open at top and bottom, and depending into a vessel 24, supported upon the tank 2, the pipe 23 passing loosely through a hole 25 in the bottom of said vessel 24. The lower end of said pipe enters loosely the top of a stationary curved pipe 26 extending through a side wall of said tank 2, the upper portion of said pipe 26 being within the tank 2 and the lower portion outside said tank, and discharging into the central section 5 of the softening chamber. A hood 27 secured around the pipe 23 extends over the open upper end of the pipe 26. A pipe 28 leads from a lower portion of the tank 2 to a pump 29, from which pump a pipe 30 leads upwardly and discharges into the top of the vessel 24, so that the vessel is always maintained full of liquid containing the reagent, part of the excess of the liquid flowing over the top edge of the vessel 24 and returning to the tank 2, and part thereof escaping through the hole 25 around the pipe 23 and falling upon the hood 27 and flowing down said hood into the tank 2. Compressed air is supplied by a pipe 31, leading either from an air pump or from a source of supply of compressed air, the latter being here shown at 32, and discharges into the lowest portion of the tank 2, the object being to agitate the reagent in said tank by means of the bubbles of air rising therethrough. An orifice 33 is formed in a side of the pipe 23, and, when no water is flowing into the vessel 9, so that the arm 11 extends horizontally, said orifice 33 is just about the top of the vessel 24, and therefore above the liquid therein, but when the arm 11 extends downwardly, then the orifice 33 in the pipe descends into the vessel 24 and liquid containing the reagent flows from the vessel 24 through said orifice 33 into said pipe 26 and then into the section 5 of the softening chamber. The softening reagent may be in solution in the water or in suspension therein, and it is in order to in-

sure that such softening agent is uniformly distributed in the water in the tank 2 and vessel 24 that it is maintained in circulation by the pump 29 and is agitated by the air 5 escaping from the pipe 31.

The pipe 4 is a by-pass pipe which is used in case larger quantities of water are to be softened or measured than the standard apparatus provides for. If the passage 10 through the pipe 4 is the same size as the passage through the pipe 8, the capacity of the feed device for water would be twice as large, one half of which is measured, the other half being by-passed direct through 15 the softening chamber. Any desired amount can be measured by by-passing more or less.

The water in which the softening reagent is uniformly distributed, flows downwardly through the central section of the softening chamber and then upwardly in an annular outer section 34 of said chamber and out by 20 a pipe 35.

A pipe 36 provided with a valve 37 can also be used to draw off the sludge from the 25 softening chamber when desired.

Supported upon the vessel 24, or in any other suitable manner, is a circular arm 40 having thereon two indicating scales 38, 39, the upper 38 indicating the rate of flow of 20 water, and the lower 39 indicating the rate of flow of the reagent, and extending from the arm 11 are upper and lower pointers 41, 42, adapted to move respectively over said scales to indicate said flow.

35 I claim:—

1. In means for automatically feeding a reagent to a stream of liquid, the combination of a distributing tank for the liquid, having a discharge hole in its bottom, a 40 balance lever, a vessel supported upon one arm of said balance lever, into which the liquid discharged through said hole enters, a reacting chamber, said vessel having a hole in its bottom through which the liquid flows 45 into the reacting chamber, a vessel for containing the reagent having a hole in its bottom, means for maintaining constant the level of the reagent in said vessel, a vertically movable pipe for discharging the reagent through said hole having an inlet 50 for the reagent, and suspended from said arm of said balance lever, and a weight suspended from another arm of said balance lever and counterbalancing the 55 weights of the vessel, when empty, and of the pipe.

2. In means for automatically feeding a reagent to a stream of liquid, the combination of a distributing tank for the liquid, 60 having a discharge hole in its bottom, a balance lever, a vessel, supported upon one arm of said balance lever, into which the liquid, discharged through said hole, enters, a reacting chamber, said vessel having a hole 65 in its bottom through which the liquid flows into the reacting chamber, a vessel for containing the reagent, a pipe movable vertically through a hole in the bottom of said vessel, said pipe having an orifice in its side, and being suspended from said arm of 70

reacting chamber, a vessel for containing the reagent, means, for maintaining constant the level of the reagent in said vessel, a pipe, movable vertically through a hole in the bottom of said vessel, said pipe having 70 an inlet for the reagent and being suspended from said arm of said balancing lever, a hood or roof on a lower part of said pipe, a lower pipe, into which upper pipe extends, covered by said hood, a weight, suspended 75 from another arm of said balancing lever and counterbalancing the weights of the vessel, when empty, and of the pipe, a tank, into which the reagent flows from the bottom and the upper edge of the vessel containing it, a pumping device, suitably connected, to draw the reagent from the last named tank and supply it to the vessel containing the reagent, and a pipe, the lower 80 end of which discharges into said reaction chamber and into the upper end of which the first-named pipe discharges, and means for agitating the reagent in the tank containing the same.

3. In means for automatically feeding a 80 reagent to a stream of liquid, the combination of a distributing tank for the liquid, having a discharge hole in its bottom, a balance lever, a vessel supported upon one arm of said balance lever, into which the 85 liquid discharged through said hole enters, a reacting chamber, said vessel having a hole in its bottom through which the liquid flows into the reacting chamber, a vessel for containing the reagent, a pipe movable vertically through a hole in the bottom of said vessel, said pipe having an inlet for the reagent, and being suspended from said arm 90 of said balance lever, a weight suspended from another arm of said balance lever, and counterbalancing the weights of the vessel, when empty, and of the pipe, a tank into which the reagent flows from the bottom and upper edge of the vessel containing it, a pump suitably connected to draw 95 the reagent from the last-named tank and supply it to the vessel containing the reagent, and a pipe the lower end of which discharges into said reacting chamber and into the upper end of which the first-named 100 pipe discharges.

4. In means for automatically feeding a reagent to a stream of liquid, the combination of a distributing tank for the liquid having a discharge hole in its bottom, a balance lever, a vessel supported upon one arm of said balance lever, into which the liquid discharged through said hole enters, a reacting chamber, said vessel having a hole 120 in its bottom through which the liquid flows into the reacting chamber, a vessel for containing the reagent, a pipe movable vertically through a hole in the bottom of said vessel, said pipe having an orifice in its side, and being suspended from said arm of 125

said balancing lever, a weight suspended from another arm of said balancing lever and counterbalancing the weights of the vessel, when empty, and of the pipe, a tank 5 into which the reagent flows from the bottom and upper edge of the vessel containing it, a pump suitably connected to draw the reagent from the last-named tank and

supply it to the vessel containing the reagent, a pipe the lower end of which discharges into said reacting chamber and into the upper end of which the first-named pipe discharges, and means for agitating the reagent in the tank containing the same. 10

OTTO BEST.
